UNITED STATES PATENT OFFICE.

NED EDGAR GOUGH, OF SEATTLE, WASHINGTON.

VALVE LIFTER.

Application filed April 12, 1921. Serial No. 460,620.

My invention relates to the art of valve removing devices or a "valve lifter" as commonly called.

More particularly my invention relates to devices for compressing the valve springs commonly found in internal combustion engines so that the holding means for said spring may be removed whereupon the valve may be extracted for grinding or replacement or the valve seat ground.

A primary object of my invention is to provide a valve lifter having a relatively long vertical thrust so that even without altering any adjustment means that may be provided thereon for the comparatively rare case, the device is at all times ready for service. I purpose providing such a device that will have but four principal members or arms and to so dispose the levers with their oscillating fulcrum points that the thrust of the depressing member will be rendered nearly vertical, so that binding of the parts will be eliminated, and the disposition of the levers and fulcrum points will be such that small angular movement of the handle is required to produce a thrust arm displacement of relatively large magnitude. Moreover, part of the time such devices must be adapted to be operated by one hand, as when removing or replacing the valve spring holding means, and obviously the operating handle should be so connected to the other arms that it moves through a relatively small angle, so that the other hand is not interrupted in its application to removing the spring pin.

Again, the device must have means that will permit of its being securely locked when desired, so locked that it will be proof against jars incident to working about the engine, and such locking means is preferably automatically removable so that the hand operating the handle is wholly free of attending to such locking means. It is a primary object of my invention to provide such a locking means and to provide means for adjusting the device for very large or very small valves.

Lastly, it is a primary object of my invention to provide such a valve removing device that is economical to manufacture, simple in operation and strong to withstand rough usage.

The above mentioned general objects of my invention, together with others inherent

in the same, are attained by the mechanism illustrated in the following drawings, the same being merely a preferred exemplary form of embodiment of my invention, throughout which drawings like reference numerals indicate like parts:

Figure 1 is a view in side elevation of a valve removing device embodying my invention applied to a valve and its spring;

Fig. 2 is a view in section on broken line 2, 2 of Fig. 1;

Fig. 3 is a view in section on broken line 3, 3 of Fig. 1; and

Fig. 4 is a view in section on broken line 4, 4 of Fig. 3.

A U-shaped arm 5 is provided on one end with a foot 6, and on the other end near its end portion with a slot 7 in which is slidably mounted a thrust arm 8. Adjustably pivotally mounted at the end portion of said arm 5 is an L-shaped fulcrum arm 9, to which arm is pivotally mounted at its upper end an L-shaped handle arm 10, said handle arm 10 being pivotally connected near its right angle point 11 to the thrust arm 8. A latch member 12 is mounted upon the handle arm 10 in operative position to engage notches 13 in the thrust arm 8. A spring 14 is preferably provided engaging said latch so that it may be automatically retracted when desired.

The mode of operation of my device is: the foot 6 is pressed against the valve spring 15 and the thrust arm 8 is caused to be positioned against the top of the valve 16 by lifting the handle arm 10 to position shown in dotted line. Thereupon, the said handle arm 10 is depressed to the position shown, i. e. with its lower part 17 approaching the vertical position of the thrust arm 8. It is preferably stopped just short of reaching the vertical so that the upwardly directed pressure on the thrust arm 8 serves to hold the latch 12 in the notches 13. If it be desired to make this device self-locking, it is only necessary to shorten the thrust arm 8 between the pivot point of the handle arm 10 and the bevelled end of said thrust arm.

Particularly, be it noted that only one hand is necessary to operate the handle arm 10 so that the other is free to remove or insert the pin 18. Upon removing the device it is only necessary to depress slightly the arm 10 so that the spring 14 automatically disengages the latch 12 and then by permit-

ting the arm 10 to rise towards the dotted line position, withdraws the thrust arm 8 in relation to the foot 6.

Manifestly, this arrangement of the L-shaped lever arms (particularly the length of part 17) provides for an unusually large vertical displacement and at the same time such displacement is accompanied with a minimum of rotation of the handle arm 10, rendering the operation of such arm 10, wholly within the power of one hand. The arm 9 is adjustably mounted by means of the holes 19.

Obviously, changes may be made in the forms, dimensions, and arrangement of the parts of my invention, without departing from the principle thereof, the above setting forth only a preferred form of embodiment.

20 I claim:

1. A valve lifter embodying a U-shaped arm, a slotted foot, on one end portion of said arm, a slot near the end portion on its other end, a thrust arm slidably mounted in said slot, said thrust arm being in alignment with said foot, an adjustable L-shaped fulcrum arm mounted in the end portion of said U-shaped arm, and an L-shaped handle arm pivotally mounted near its angle point to said thrust arm and pivotally connected at its end portion to the end of said fulcrum arm.

2. A valve lifter embodying a U-shaped arm, a slotted foot on one end portion of said arm, a slot near the end portion on its other end, a thrust arm slidably mounted in said slot, said thrust arm being in alignment with said foot, an adjustable L-shaped fulcrum arm mounted in the end portion of said U-shaped arm, an L-shaped handle arm pivotally mounted near its angle point to said thrust arm and pivotally connected at its end portion to the end of said fulcrum arm, and a locking latch operatively mounted on said handle arm and disposed to engage said thrust arm.

3. A valve lifter embodying a U-shaped arm, a slotted foot on one end portion of

said arm, a slot near the end portion on its other end, a thrust arm slidably mounted in said slot, said thrust arm being in alignment with said foot, an adjustable L-shaped fulcrum arm mounted in the end portion of said U-shaped arm, an L-shaped handle arm pivotally mounted near its angle point to said thrust arm and pivotally connected at its end portion to the end of said fulcrum arm, a locking latch operatively mounted on said handle arm and disposed to engage said thrust arm, and a spring connected to said latch whereby said latch may be automatically retracted.

4. A valve lifter embodying a U-shaped arm, formed by fixedly securing two flat members together as respects their middle and one end portion; an adjustable slotted foot being disposed on one end portion of said arm; a slot near the end portion on its other end; a thrust arm slidably mounted in said slot, said thrust arm being in alignment with said foot; an adjustable L-shaped fulcrum arm mounted in the end portion of said U-shaped arm; and an L-shaped handle arm pivotally mounted near its angle point to said thrust arm and pivotally connected at its end portion to the end of said fulcrum arm, whereby a small angular movement of said handle arm results in a relatively large displacement of said thrust arm.

5. In a valve lifter device, a thrust arm, a U-shaped arm on one end portion of which said thrust arm is operatively slidably mounted, an L-shaped handle pivotally connected to a pivotally mounted fulcrum arm, said pivotal connection of said handle and said fulcrum arm being at the end thereof, said handle being pivotally mounted near its angle point to said thrust arm, and said fulcrum arm being pivotally mounted at one end portion to said U-shaped arm, and the other end pivotally mounted to said thrust arm.

In witness whereof, I hereunto subscribe my name this 2nd day of April, 1921.

NED EDGAR GOUGH.
